F. E. GLADWIN

WALL CONSTRUCTION

Filed Feb. 8, 1923

Inventor;
Frederic E. Gladwin,
per Arthur J. Farnsworth.
Attorney.

UNITED STATES PATENT OFFICE.

FREDERIC E. GLADWIN, OF LOS ANGELES, CALIFORNIA.

WALL CONSTRUCTION.

Application filed February 8, 1923. Serial No. 617,827.

To all whom it may concern:

Be it known that I, FREDERIC E. GLADWIN, a citizen of the United States, residing at Los Angeles, in the county of Los Angeles and State of California, have invented a new and useful Wall Construction, of which the following is a specification.

My invention relates to wall construction involving the use of tile and concrete; and the objects of my invention are, first, to provide a method whereby the inner and outer faces of a wall may be built up of tile subsequently filled with concrete, thus eliminating the expense of forms; second, to afford facilities for tying said inner and outer faces together in such a manner that walls of different thickness may be constructed by the use of suitable ties of standard length; and, third, to supply a tie that will make it possible to accomplish the aforesaid objects.

Other objects and advantages of my invention will appear hereinafter, and while I show herewith and will describe a preferred form of construction, I desire to be understood that I do not limit myself to such form, since various changes and adaptations may be made therein without departing from the spirit of my invention as hereinafter claimed.

My construction is illustrated in the accompanying drawing, in which—

Figure 1 is a perspective view of a cornered wall, in course of construction in accordance with my improved method; Figure 2 is a plan view of a similar wall illustrating how various wall thicknesses may be had by the use of a tie of standard length; Figure 3 is a perspective view of a preferred form of tile for use in connection with my method; Figure 4 is a side elevation of a standard form of tie; and Figures 5 and 6 respectively are side and end elevational views of a twisted pair of the ties illustrated in Figure 4.

Similar numerals refer to similar parts throughout the several views.

My method of construction consists essentially of laying up inner and outer walls of tile, spaced and tied together in such a manner as to obviate bulging or other displacements, and then pouring concrete between them. This method entirely eliminates the necessity for building concrete wall forms; and the slow and difficult processes of applying tile in a satisfactory manner to concrete walls that have previously been built.

Any suitable size, thickness, and surface finish of tile may be used in connection with my method. If desired glazed finish tile may be used for the outside surface, and rough tile, adapted for receiving a plaster coat, for the inside surface of the wall. When completed, a wall constructed as herein described will not only have each tile rigidly anchored to co-operating tiles on the opposite face, but each tile will be thoroughly bonded to the concrete core as well.

The tiles 7 used in my construction are provided with spaced holes in the upper and lower edges, for engagement by the ties. One such hole is shown at 8 in Fig. 3, which also indicates how, in the case of relatively thin tiles, they may be thickened as at 9 where the holes occur. This method permits of using a relatively large tie hole in a thin tile without danger of the hole breaking out as a result of the pressure of the concrete when the latter is being poured. Tiles similar to that illustrated in Fig. 3 are also shown in Fig. 2. In Fig. 1 thicker tiles, without the thickened portions, are shown.

The ties may be made in the form of thin steel rods 10 with their ends bent at right angles as shown most clearly in Fig. 4 and the left hand end of Fig. 1 where indicated by arrow 11. Or a pair of such ties may be twisted together to form the composite tie 12. The latter form is illustrated in side and end elevational views in Figs. 5 and 6 respectively, and is shown as used in the top course of the wall depicted in Fig. 1. In the case of these composite ties the bent ends of their respective elements are so arranged as to extend in opposite directions as indicated.

The spacing of the edge holes in the tiles, for the accommodation of the ties, should preferably be uniform when the tiles are laid up. These holes therefore are located at points $\frac{1}{4}$ the length of the tile from each end. This uniform spacing of the holes insures that the ties are in parallel relation, and permits placing the inner and outer faces of the wall any desired distance apart within the limits of the length of the ties.

This method of employing standard length ties for varying wall thicknesses is illustrated in Fig. 2. The solid line portion of this figure shows a relatively thin wall with ties 10 disposed at acute angles thereto. The upper face of this wall however could equally well have been laid up in the posi-

tion shown in dotted lines, which would have resulted in a completed wall of over twice the thickness; or it could have been laid up in any intermediate position, resulting in a finished wall of intermediate thickness.

It should be noted that if the upper face of tiles shown in Fig. 2 is swung upward to the position shown dotted, the vertical joints will come opposite the joints in the lower face. This is objectionable and may be avoided by shifting the tiles longitudinally a distance equal to half their length, and placing the tie in the hole at the other end of the tile. This has been done in the dotted view of Fig. 2, where the joints of the dotted course break with the joints of the bottom solid course. It is always possible to break vertical joints in the inner and outer tile faces of a wall in this manner.

In building a wall in accordance with my improved method, one or two courses of both the inner and outer tile faces are first laid up with ties at the proper angles to give the desired wall thickness. If plain ties 10 are used, they must be employed as shown at 11 in Fig. 1, so that both the lower and top edges of the tile are tied. Obviously the composite tie 12 serves the purpose of a pair of the others, but is otherwise similarly used. The composite form is usually more convenient.

After a few courses of tile are laid up in this manner, concrete is poured between the two facings as indicated in Fig. 1, and afterward these operations are repeated in sequence until the wall is complete.

It will be seen that bulging of the wall due to the pressure of the fluid concrete, which at first sight seems possible on account of the angular position of the ties, is pre-

vented by the abutting action of adjacent tiles. It would be impossible for any tile, constrained as it is by the ties, to move outwardly without at the same time moving longitudinally. The latter movement is prevented by the adjacent row of abutting tiles.

Attention is particularly directed to the corner construction shown in Fig. 1. The corner tiles are as fully and completely tied as the others, but in this case a few ties of special or altered length may have to be employed.

The foregoing description has made it clear that the relatively great expense of concrete wall forms may be completely eliminated. It is also clear that there will be a great saving in the labor cost of tile setting, since it is far cheaper to lay the tiles in courses in the manner indicated, than to apply them to the face of a concrete wall that has been completed. Moreover it is frequently very difficult to attach tiles to a finished wall in a permanently satisfactory manner.

Having thus fully described my invention in such a way that it will be clear to any one familiar with this art, I claim;

1. A wall construction of spaced, opposed tile courses, ties obliquely connecting the tiles in their respective courses, the space between the courses being concrete filled.

2. A wall construction of spaced, opposed tile courses, ties obliquely connecting the tiles in their respective courses, the space between the courses being concrete filled; said ties being pivotally connected to the tiles so that the spacing of the courses may be varied at the beginning of construction by varying the obliquity of the ties.

FREDERIC E. GLADWIN.
